UNITED STATES PATENT OFFICE.

CHARLES FAYER, OF NEW YORK, N. Y., ASSIGNOR TO WAPPLER ELECTRIC COMPANY,
INC., A CORPORATION OF NEW YORK.

COIL-WINDING MACHINE.

Application filed January 4, 1921. Serial No. 435,000.

To all whom it may concern:

Be it known that I, CHARLES FAYER, a citizen of the United States, residing at New York, county of New York, and State 5 of New York, have invented certain new and useful Improvements in Coil-Winding Machines, of which the following is a full, clear, and concise description.

My invention relates to coil winding machines; that is, to machines used for the purpose of winding coils of the type used for producing high tension currents, impulses and discharges, and particularly such coils as are employed in radiographic and X-ray 15 work.

More particularly stated, my invention contemplates improved mechanism for automatically stopping and starting the winding drum, and for so regulating the distribution 20 of the wire as wound thereupon as to cause the stoppage of the drum to take place at exactly the proper instant required by the distribution of the wire upon the drum. That is to say, I make specific provision for 25 the drum to stop turning at the instant when the wire, as wound upon the drum, is completely formed into a layer of a single thickness of the wire.

My invention further contemplates the arrangement and adaptation of the mechanism just mentioned, for use in connection with other mechanism, controllable directly by hand, for winding upon the drum a fillet or ribbon of paper or other flexible insulating 30 material, and for cutting off this fillet periodically in order for it to be formed into bands disposed concentrically, without interfering with the continuity of the wire, or with the proper distribution of the 35 convolutions thereof.

My invention further contemplates an improved stop-motion, specially adapted for use with mechanism of the kind above mentioned.

Reference is made to the accompanying drawings forming a part of this specification, and in which like letters indicate like parts throughout the several figures.

Figure 1 is a side elevation of my improved coil winding machine.

Figure 2 is an end elevation of the same.

Figure 3 is a diagram of the wiring, and parts immediately associated therewith.

Mounted upon a base plate 4 are a number

of posts 5, 6, 7 and 8, and a frame 9. These 55 parts being used for supporting various portions of the mechanism. The frame is provided with slots 10, 11 arranged in pairs and are used for supporting rolls of paper 12, 13, the slots 10, 11 being for the purpose of 60 facilitating the removal and replacement of the rolls of paper. Strips 14, 15 are wound off of these rolls of paper and formed into a fillet 16, which is thus of two ply paper. Either or both of the strips of paper 14, 15 65 may be prepared with an adhesive surface for this purpose. The fillet 16 passes between a pair of presser rolls 17.

A shear 18 is provided for the purpose of severing the fillet 16 at intervals, thus cutting 70 it into lengths as desired.

A winding drum is shown at 19, and is used for supporting the coil as wound. This drum carries a cylinder 20, of fiber or other insulating material. The drum is supported 75 upon a revolvable shaft 21, and is provided with a pair of end guards 22, 23, each having the proximate form of a disk.

A brace 24 is mounted upon the posts 6, 7 and is secured to bearings 25, 26 with 80 which these posts are provided. A counter is shown at 27, and is mounted upon the brace 24, the latter serving as a beam for supporting the counter.

Mounted upon the shaft 21 is a pulley 28 85 for communicating motion to other parts as hereinafter described.

A starting box 29 is mounted upon the post 5. Wires 31, 32, preferably formed into a cable 33 lead from a source of electricity, not shown, to the starting box 29.

A pair of wires 34, 35 lead from the starting box 29 to the counter 27, for the purpose of enabling the counter to automatically control the starting box, if this be desirable. 95 The starting box is provided with a push button 30 and a main switch 32.

An electric motor is shown at 36, and is provided with a sleeve 37 serving as a bearing. Extending through this sleeve is a 100 rod 38, provided with a grip handle 39, the latter having a slot 40. The rod 38 extends through the grip handle 39, and carries a clutch pin 41. The operator, by grasping the grip handle 39 and shifting the same to the right or left so as to cause the clutch pin 41 to enter or leave the slot 40, can throw the shaft 21 into or out of working relation 105

with the electric motor 36. A wire 42 leads from the push button 30 in the starting box 29 to the motor 36, and a wire 43 leads from the main switch 32^a to a binding post 46 carried by a circuit breaker 48. Another binding post 47 is carried by this circuit breaker, and connected with this binding post is a wire 44. A wire 44^a is connected with the motor 36. The wires 44, 44^a are 10 provided with additional connections, and are used as hereinafter more fully described.

A belt 49 engages the pulley 28 and also engages a pulley 50, the latter being mounted upon a revoluble shaft 51. This shaft is 15 supported upon an arm 52 serving as a bearing. The shaft 51 carries a worm 53, which engages a worm gear 54. The worm gear 54 carries a pair of presser pins 55, 56, disposed diametrically opposite each 20 other and each located adjacent the edge of the gear. A contact member 57 extends through and is supported by a plate 58 of insulating material, and a contact member 59 is mounted upon and carried by an 25 arm 60. The arm 60 is made of metal, and is mounted upon a bearing 61. The arm 60 carries a presser knob 62, which is rounded as shown in Figure 3, and located partially in the path of travel of each of the presser 30 pins 55, 56. The parts just described are so formed and arranged that either one of the presser pins 55, 56, coming into engagement with the presser knob 62, causes the arm 60 to swing slightly in a clockwise direction 35 according to Figure 3, and thus move the contact member 59 out of engagement with the contact member 57. A spring 63 is used for the purpose of shifting the arm 60 back into its normal position—that is into such 40 position that the contact member 59 is in engagement with the contact member 57.

The worm gear 54 carries a heart cam 64, and engaging this heart cam is a pin 65, carried by a swinging arm 66. A spring 67 45 engages the pin 65, and constantly presses the same against the edge of the heart cam. The spring 67 is mounted upon a stationary arm 68.

The swinging arm 66 has the form indicated more particularly in Figure 1, and is provided with a slot 70. The swinging arm 66 carries a bearing 71, which is slidably adjustable along the upper portion of the arm, by aid of the slot 70. The bearing 71 carries a pulley 72, which is thus adjustable relatively to the swinging arm and supported thereon.

Mounted upon the post 8 is a bearing 73^a, carrying an arm 75, the latter supporting 60 a spool 74. A wire 73 is reeled off from the spool, and passes over a pulley 76 and under the pulley 72, being thence wound around the drum 19, as may be understood from Figure 2.

65 The pulley 76 is carried by a pulley

block 77, and this pulley block is supported upon a cord 78, the cord being partially wound around a lifting drum 79. This drum is supported by a stationary shaft 80. The cord 78 carries a tripping block 81, which may be brought into engagement with a contact arm 82 whenever the cord 78 is wound up and the pulley 76 thereby raised by means of the lifting drum 79.

A tubular block 83 serves as a limiting 75 stop for preventing excessive upward travel of the contact arm 82, as may be understood from Figure 3.

The contact arm 82 carries a plate 84, and from the latter a guide rod 85 extends 80 downwardly. Loosely encircling this guide rod is an eye 86, carried by the pulley block 77. By this arrangement the pulley block 77 is in its up and down movements guided by the guide rod 85, so as to cause the 85 tripping block 8, in its upward travel, to be brought accurately and positively into engagement with the adjacent end of the contact arm 82, as indicated more particularly in Figure 3.

The contact arm 82 carries a contact boss 87, and adjacent the latter is another contact boss 88. The contact boss 88 is mounted upon a metallic strip 89, and mounted upon this strip is a binding post 90. The strip 89 and another binding post 91 are mounted upon a board 92. The contact arm 82 is pivotally supported below the board 92, and is engaged by a spring 93, whereby it is always maintained under 100 a gentle tension. Thus the contact consisting of the bosses 87, 88 is normally closed, but is opened whenever the pulley block 77 is raised to its upper limit of travel. The board 92 and parts immediately associated therewith are supported by a stationary 105 arm 94, the latter being mounted upon the upper portion of the post 8.

For the purpose of properly tensioning and centering the spool 74 I provide a plunger 95, encircled by a spring 96 and extending through a sleeve 97. This sleeve is provided with an arm 99, and extending through a hole in the latter is a guide rod 98.

The wiring employed is shown diagrammatically in Figure 3. The board 92 with its accompanying parts including the contact arm 82 is essentially a circuit breaker, and this circuit breaker is in series with the circuit breaker 48, which is provided as 115 above explained with the contact arm 60. Thus the circuit of the system contains two contacts arranged in series with each other and with the motor 36, and so arranged that the opening of either contact will stop 120 the motor if the latter be running.

The normal or working circuit of the system may be traced as follows: wire 31, motor 36, wire 44^a, circuit breaker 92, wire 44, circuit breaker 48, wire 43, main switch 130

32^a, wire 32 to source of electricity, not shown, and thence back to wire 31.

If, however, the circuit just traced happens to be open owing to the position occupied by either of the contact arms 60 or 82, so that the motor is not energized, the push button 30, contained in the starting box 29, may be closed by hand and another circuit through the motor may now be traced as follows: wire 31, motor 36, wire 42, push button 30, main switch 32^a, wire 32 to source of electricity, not shown, thence back to wire 31.

The swinging arm 66, the heart cam 64 and various other parts immediately associated with these parts are so proportioned and arranged, relatively to the drum 19, that each complete swing of the arm 66 carries the pulley 72 a distance approximating the width of the drum 19. Since, however, it may happen that coils of different sizes are to be wound upon this drum, or in other words since the drum may be virtually wider at one time than at another, the distance traveled by the pulley should be varied accordingly. The operator by adjusting the position of the slide 71 may within reasonable limits vary the length of the stroke or distance of travel of the pulley 76.

The operation of my device is as follows:

The various parts being assembled and arranged as above described, and being in their respective normal positions, the device is operated as set forth below.

I will assume that the electric motor is running, and that the swinging arm 66, the heart cam 64 and various other movable parts occupy the respective positions indicated for them in Figure 3. The swinging arm 66 is now swinging to the right according to this figure, and the heart cam is turning in a contra-clockwise direction, so that the presser pin 56 is approaching the presser knob 62 and the presser pin 56 is receding therefrom. By the time the swinging arm 66 reaches the limit of its travel to the right, the presser pin 56 engages the presser knob 62 and rocks the arm 60 in a clockwise direction, so that the contact member 59 is moved out of engagement with the contact member 57. This breaks the motor circuit and thereby stops the motor, so that the various movable parts are brought to a standstill.

The swinging movement of the arm 66 to the right, as just described, carries the pulley 72 to a distance corresponding to the width of the drum 19, so that the wire 73 is so delivered to this drum and so wound thereupon as to form a single unbroken layer. When the motor stops as just stated, the operator brings the end of the fillet 16 into contact with the layer of wire just wound upon the drum 19, and by turning

the drum a single revolution by hand, coils the fillet upon the drum, so as to form a band or ring, the end of the fillet being overlapped by another portion of the fillet. The operator then actuates the shear 18, and 70 severs the fillet, the portion thus cut off being of course so disposed as to completely cover the layer of wire. The wire 73 is not severed, however. The operator next starts the motor into action, and for this purpose 75 closes the push button 30, or in other words short-circuits the circuit breakers. This is only for an instant, however, because as soon as the motor begins to run the rotation of the gear wheel 54 carries the presser pin 80 56 out of engagement with the presser knob 62, so that the arm 60, under pressure from the spring 63, now rocks slightly in a contra-clockwise direction and this brings the contact member 59 into engagement with the contact member 57. This closes the motor 85 circuit independently of the push button 30, so that the motor continues running after pressure upon the push button is relaxed. The motor continues running until the presser pin 55 engages the presser knob 62 and thus causes the arm 60 to rock slightly as before and again open the motor circuit, stopping the motor as before. Thus the swinging arm 66 swings first to the right 90 and stops, and then swings to the left and stops, each swing of the arm in either direction resulting in a single layer of wire being wound around the drum, the operator being allowed time, after the layer is in position, 95 to wind around it a fillet of paper or other flexible insulating material.

Suppose, next, that the wire 73 breaks from any cause, usually accidental, or that the wire becomes exhausted. This frees the pulley 76, heretofore held down in its normal position by the tension of the wire, and as a result the pulley block 77, carrying the pulley 76, is lifted upward by means of the lifting drum 79, acting upon the cord 78. 105 As the pulley block 77 rises, the tripping block 81 engages the contact arm 82, and by rocking it slightly as indicated in Figure 3, moves the contact member 87 out of engagement with the contact member 88. 110 This opens the motor circuit and stops the motor and all movable parts driven thereby. The operator may now start up the motor by pressing upon the push button 30, so as to short-circuit the circuit breakers as above 115 described, and the motor thus started will continue to run so long as the push button is kept closed. The broken wire being repaired, or a new spool of wire being supplied and properly connected, closure of the 120 push button starts up the motor and the latter continues to run until stopped as above described by the opening of the motor circuit when the arm 66 is at the limit of its travel in either of two directions; in other 125 130

words, until either the presser pin 55 or the presser pin 56 engages the presser knob 62 and rocks the arm 60.

I do not limit myself to the precise mechanism shown and described, as variations may be made therein without departing from the spirit of my invention, the scope of which is commensurate with my claims.

Having thus described my invention, what I claim as new and desire to secure by Letters Patent is as follows:

1. In a device of the character described, the combination of a winding drum, gearing for turning the same, dispensing mechanism connected with said gearing and driven thereby for feeding wire to said drum in the form of a distinct layer, an electric motor connected with said gearing for the purpose of actuating the same, a circuit for energizing said motor, and mechanism connected with said gearing and with said circuit, and driven positively by said gearing, for opening said circuit when said dispensing mechanism finishes said distinct layer.

2. In a device of the character described the combination, with a winding drum and gearing for turning the same, of dispensing mechanism connected with said gearing and actuated thereby for dispensing wire to said drum in the form of distinct layers, an electric motor connected with said gearing for the purpose of actuating said winding drum and said dispensing mechanism, an electric circuit for energizing said motor, a contact for opening said circuit, and mechanism connected with said contact and with said gearing, and controllable by positive movements of said gearing, for opening said contact and thereby de-energizing said circuit.

3. In a device of the character described the combination, with a winding drum and gearing for turning the same, of dispensing mechanism connected with said gearing and actuated thereby for dispensing wire to said drum in the form of distinct layers, an electric motor connected with said gearing so as to actuate said gearing, an electric circuit for energizing said electric motor, a contact included within said circuit for the purpose of opening and closing said circuit, an arm connected with said contact for the purpose of actuating the same, and a revolute member connected with said gearing and with said arm, and driven by said gearing, for actuating said arm periodically.

4. In a device of the character described the combination, with a winding drum and gearing for turning the same, of a source for supplying wire to be wound upon the drum, a swinging arm provided with means for guiding said wire as wound upon said drum, said swinging arm having a swinging movement back and forth and having a dis-

tance of travel in each of two directions approximately equal to the width of the drum, so as to deposit a single complete layer of said wire upon said drum for each swinging movement of said arm in either of said two directions, and mechanism connected with said gearing and with said swinging arm, and controllable by positive movements of said gearing in synchronism with the swinging movements of said arm, for periodically stopping the movements of said gearing.

5. In a device of the character described the combination, with a winding drum and gearing for actuating the same, of a magazine for supplying wire to be wound upon the drum, a swinging arm provided with means for guiding said wire as wound upon said drum, said swinging arm having a travel in each of two directions approximately equal to the width of said drum, so that for each complete swinging movement of said arm in either direction a single complete layer of wire is deposited upon said drum, an electric motor connected with said gearing in order to actuate said drum and said swinging arm, a circuit connected with said motor for energizing said motor, and circuit breaking mechanism connected with said circuit for the purpose of periodically opening the same, said circuit breaking mechanism being connected with said gearing and controllable directly by positive movements thereof, the parts being so proportioned that said circuit breaking mechanism is actuated to break said circuit at the instant when the travel of said swinging arm in either direction is completed.

6. In a device of the character described the combination, with a winding drum and gearing for turning the same, of a source of wire to be wound upon the drum, a swinging arm provided with means for guiding said wire as wound upon said drum, said swinging arm having a travel in each of two directions approximately equal to the width of said drum, so that for each complete swinging movement of said arm in either of two directions a single complete layer of wire is deposited upon said drum, an electric motor connected with said gearing, means controllable by said gearing for actuating said swinging arm, an electric circuit connected with said motor for energizing said motor, and mechanism connected with said electric circuit and with said gearing and controllable by said gearing for periodically opening said electric circuit.

7. In a device of the character described the combination, with a winding drum and gearing for turning the same, of means for supplying a wire to be wound upon said drum, a swinging arm provided with means for guiding said wire as wound upon said drum, said swinging arm having a travel

in each of two directions approximately equal to the width of said drum, so that for each complete swinging movement of said arm in either of two directions a single complete layer of wire is deposited upon said drum, an electric motor connected with said gearing for actuating the same, an electric circuit for energizing said motor, contact mechanism connected with said circuit for 5 opening said circuit in order to stop said motor, a revolute member for actuating said contact mechanism in order to open said circuit, a heart cam carried by said revolute member and provided with means 10 for actuating said swinging arm, and driving connections from said gearing to said revolute member.

8. In a device of the character described the combination, with a winding drum together with means for supplying a wire to 15 be wound upon said drum and gearing for

turning said drum, of a swinging arm for controlling the distribution of said wire as wound upon said drum, said swinging arm having a travel in each of two directions 25 approximately equal to the width of said drum, so that for each complete swinging movement of said arm in either of two directions a single complete layer of wire is wound upon said drum, gearing for actuating said drum and said swinging arm, an electric motor for driving said gearing, an electric circuit connected with said motor for energizing the same, contact mechanism 30 included in said circuit for the purpose of opening said circuit in order to stop said motor, and mechanism connected with said contact mechanism and with the wire and controllable by the breaking or exhaustion 35 of the wire for opening said contact mechanism. 40

CHARLES FAYER.
